UNITED STATES PATENT OFFICE.

WALLACE RUTHERFORD HARRIS, OF LOUISVILLE, KENTUCKY.

FILE-WRAPPER.

No. 910,194.

Specification of Letters Patent.

Patented Jan. 19, 1909.

Application filed February 6, 1908. Serial No. 414,491.

To all whom it may concern:

Be it known that I, WALLACE R. HARRIS, a citizen of the United States, and a resident of Louisville, in the county of Jefferson and State of Kentucky, have invented a new and Improved File-Wrapper, of which the following is a full, clear, and exact description.

This invention relates to file wrappers, and it is particularly useful in connection 10 with vertical filing systems.

More specifically, the invention relates to file wrappers which comprise backs and covers, between which the papers to be filed can be inserted, and which have removable, 15 centrally-disposed means for fastening the papers to be filed, in position.

An object of the invention is to provide a simple and inexpensive file wrapper which prevents the loss of the papers to be filed, 20 which keeps them smooth and in good condition, and in which the papers can be filed with rapidity and ease.

A further object of the invention is to provide a file wrapper which is of large 25 capacity, which is especially well adapted for use in connection with vertical filing systems, and in which is employed a removable clasp or fastening so that if desired, the same can be dispensed with and the papers 30 filed between the back and the cover of the wrapper without securing the papers to one or the other of the same.

The invention consists in the construction and combination of the parts to be more 35 fully described hereinafter and particularly set forth in the claims.

Reference is to be had to the accompanying drawings forming a part of this specification, in which similar characters of reference indicate corresponding parts in all the 40 views, and in which—

Figure 1 is a plan view of the body of the wrapper extended, showing the folds or plicatures of the body which form it into the 45 back, cover and the flap for the clasp or fastener; Fig. 2 is a perspective view showing the wrapper with papers filed therein; Fig. 3 is an enlarged longitudinal, partial section of the wrapper, showing certain of 50 the parts in different positions in dotted outlines; and Fig. 4 is a similar view showing the wrapper with papers filed therein.

Before proceeding to a more detailed explanation of my invention, it should be understood that while the same is particularly useful in connection with vertical filing

systems in which the papers to be filed are arranged in classified groups, and in which each group is filed in a special envelop, the invention can be advantageously employed 60 in other filing or similar systems in which the papers, documents or the like are grouped and filed in groups, each group being inclosed or contained in a suitable wrapper.

In many filing systems the papers are 65 merely loosely arranged in the wrappers, and consequently there is danger of one or more of the papers being accidentally displaced from the wrapper, and lost. Furthermore, the papers in each of the wrappers 70 can easily become disarranged and crumpled or otherwise injured.

With my invention, the papers, if so desired, can be securely held in position in the wrapper by means of a suitable fastener. 75 This fastener may be of any preferred or common form, though I have found it useful to employ the ordinary fastener which consists of a head and bendable legs or prongs, which can be forced through the paper and 80 then disposed to one side, whereby the fastener becomes firmly attached to the paper.

My wrapper has a particular part for the attachment of the fastener, and this part is strengthened and reinforced so that the fastener 85 cannot be torn loose by accident.

It will be understood that the wrapper can be fashioned from any suitable material such, for example, as stiff paper or the like. The size, moreover, forms no part of the 90 invention but the wrappers may be of various sizes and shapes to adapt them for the filing of papers, documents and the like of different size and form.

Referring more particularly to the drawings, 10 represents the body from which the wrapper is formed. Near the middle, the body has a plicature or fold 11 to permit the body to be bent or folded upon itself, whereby is formed the back 12 and the cover 13 between which the papers to be filed are inserted. The back 12 has an extension 14 adapted to have inscribed or otherwise marked thereon, indicating numerals, reference letters or the like, to identify the 100 contents of the file wrapper. The extension 14 projects beyond the edge of the cover 13 when the latter is folded against the back, so that the indicating marks on the extension 105 can be easily seen without opening the wrapper. The back portion of the body 12 is extended to form a flap 15 which is separated 110

from the back 12 by a fold or plicature 16. The latter permits the flap to be bent or folded into position between the back and the cover. A double reinforcing strip 17 is 5 glued or otherwise fastened to the flap 15 at each side thereof, substantially near the middle. A fastener or clasp 18 is mounted upon the flap 15, by being inserted in an opening extending through the reinforcing strip and 10 the flap. The arrangement is such that the head 19 of the fastener is arranged between the flap and the back 12 when the flap is folded over against the back, while the prongs 20 of the fastener extend outwardly 15 from the back so that the letters or other papers can be easily secured thereto. Usually the papers to be filed will have openings formed therein through which the prongs are passed and then bent over, as is shown 20 most clearly in Fig. 2.

As the fastener is held in position at the back, the person filing the papers has both hands free for the insertion of the papers in the wrapper; thus the operation of filing can 25 be more rapidly executed than is usually the case. The fasteners can be removed by simply withdrawing them from the opening in the flaps, and the papers can then be filed by merely placing them in position between the 30 back and the cover and under the flap.

Having thus described my invention, I claim as new and desire to secure by Letters Patent:—

1. A file wrapper, comprising a body hav-

ing plicatures whereby it is formed into a 35 back, a cover, and at said back a flap adapted to be folded into position intermediate said cover and said back, and a fastener removably carried by said flap, said fastener serving to hold papers in position between said 40 back and said cover, said back having an extension projecting beyond said cover when the latter is folded into a closed position, and serving to have identifying characters indicated thereon.

2. A file wrapper, comprising a body having a back, a cover, and at said back a flap having a reinforced portion, and a fastener removably carried by said flap at said reinforced portion, and serving to hold papers 50 in position between said back and said cover.

3. A file wrapper, comprising a body having plicatures whereby it is formed into a back, a cover, and at said back a flap, said flap having a reinforcing strip, a fastener 55 carried by said flap at said reinforcing strip, in such a manner that the head of said fastener is positioned between said back and said flap when the latter is folded into position against said back, said strip being arranged near the middle of said flap.

In testimony whereof I have signed my name to this specification in the presence of two subscribing witnesses.

WALLACE RUTHERFORD HARRIS.
